US0D1039176S

(12) **United States Design Patent** (10) **Patent No.:** **US D1,039,176 S**
(45) **Date of Patent:** **** Aug. 13, 2024**

(54) **STAIR HANDRAIL**

(71) Applicant: **Jinan Yuxi Electronic Commerce Co., Ltd.**, Jinan (CN)

(72) Inventor: **Zhenhua Hu**, Jinan (CN)

(**) Term: **15 Years**

(21) Appl. No.: **29/845,972**

(22) Filed: **Jul. 12, 2022**

(51) LOC (14) Cl. **25-02**

(52) U.S. Cl.

USPC **D25/41.1**

Primary Examiner — Leanne Was-Englehart

(57) **CLAIM**

The ornamental design for an stair handrail, as shown and described.

DESCRIPTION

FIG. 1 is a perspective view of an stair handrail, showing my new design;

FIG. 2 is another perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof; and,

FIG. 8 is a bottom plan view thereof.
